US0D1071682S

(12) **United States Design Patent** (10) **Patent No.:** **US D1,071,682 S**
(45) **Date of Patent:** **** Apr. 22, 2025**

(54) **WRENCH**

(71) Applicant: **Apex Brands, Inc.**, Apex, NC (US)

(72) Inventors: **Zhihong Fu**, Cary, NC (US); **Noah Thomas Steen**, Cary, NC (US); **Kyle Romanick**, Fuquay-Varina, NC (US); **Jenny Appleton**, Apex, NC (US)

(73) Assignee: **Apex Brands, Inc.**, Apex, NC (US)

(**) Term: **15 Years**

(21) Appl. No.: **29/885,853**

(22) Filed: **Mar. 1, 2023**

(51) LOC (15) Cl. **08-05**

(52) U.S. Cl.

USPC **D8/28**

(58) **Field of Classification Search**

(57) **CLAIM**

The ornamental design for a wrench, as shown and described.

DESCRIPTION

FIG. 1 is a perspective view of a wrench with a highlighted portion corresponding to the view shown in FIG. 8; FIG. 2 is a left side view of the wrench of FIG. 1; FIG. 3 is a right side view of the wrench of FIG. 1; FIG. 4 is a front view of the wrench of FIG. 1; FIG. 5 is a rear view of the wrench of FIG. 1; FIG. 6 is a top view of the wrench of FIG. 1; FIG. 7 is a bottom view of the wrench of FIG. 1; and, FIG. 8 is a perspective view of the highlighted portion shown in FIG. 1.

The broken lines of FIGS. 1-8 are illustrative of the visible environmental structure of the wrench and form no part of the claimed design.

1 Claim, 5 Drawing Sheets
